Application September 11, 1934, Serial No. 743,531

35 Claims. (Cl. 66—178)

This application is a continuation in part of my co-pending application Ser. No. 645,919, filed December 6, 1932, now Patent No. 2,011,267, August 13, 1935 and is in part a continuation as to 5 common subject matter of my co-pending applications Ser. No. 541,245, filed June 1, 1931 now Patent No. 1,989,913, Feb. 5, 1935, and Ser. No. 613,244, filed May 24, 1932.

In order that the principle of the invention 10 may be readily understood, I have in the accompanying drawings shown two embodiments of my invention in each of which there is disclosed a fashioned knitted stocking blank having a main or weft knitting thread, and a warp 15 thread for each needle wale of the fabric, such blank being fashioned by the transfer in selected courses of warp and weft loops in fashioning or narrowing.

In this application I claim broadly the transferring for narrowing or fashioning of stitches 20 composed of loops of the main knitting thread and of the correlated or corresponding warp threads, but I do not herein claim the more specific matter or invention involving the continuing of the knitting of needle wales with warp 25 threads therein, past the narrowings made by transferring such stitches whether to the toe of the stocking or to some intermediate point, as that is claimed in my co-pending application 30 Ser. No. 700,193, filed November 29, 1933, now Patent No. 1,978,408.

My invention in its broadest aspect is not limited to a warp thread to each needle wale of a flat knit fabric, inasmuch as it comprehends a shaped or fashioned knitted fabric having 35 courses composed of a knitted body thread, and of a series of warp threads extending lengthwise the fabric and respectively knitted in loops in successive courses into different loops of said 40 body thread in such courses and including fashioning needle wales of the fabric, stitches at the shaped or fashioned areas of said fabric being each composed of a loop of said body thread and a loop of one of said warp threads, together 45 laterally transferred, thereby to shape or fashion the said fabric.

Fig. 1 is a plan view of a blank of an English type of full fashioned or flat-knit stocking having 50 my invention, as above stated, applied thereto; said blank representing the knitting thereof through the leg and the top of the foot down to the toe and representing the heel tabs as they appear in the blank before the same are cut, the said figure representing the first embodiment of the invention herein referred to;

Fig. 2 is a view of the same blank after the parts constituting the bottom of the foot and the toe have been knitted thereonto;

Fig. 3 is a plan view of a portion of the fabric at the narrowings, said view corresponding to 5 a photograph of the fabric as made by a microscopic camera;

Fig. 4 is a detail on a small scale of a portion of the fabric blank at the narrowings on 10 one side;

Fig. 5 represents a plan view of the upper portion of a blank for a full fashioned or flat-knit stocking (parts being broken away) made in accordance with the second embodiment of the 15 invention herein referred to;

Figs. 6 and 7 are plan views of the blank shown in Fig. 5 at subsequent stages of the manufacture thereof, that shown in Fig. 6 representing the knitting of the instep down to the toe and that represented in Fig. 7 indicating the completion of the blank by the knitting of the 20 bottom of the foot and the toe;

Fig. 8 is a side elevation of a full fashioned or flat-knit stocking made either from the blank 25 shown in Figs. 1 and 2 or from the blank shown in Figs. 5, 6 and 7; and

Fig. 9 is a greatly enlarged representation of 30 stitches of the fabric including certain of the narrowings when the blank is made in accordance with the second herein disclosed embodiment of the invention.

Referring first to that embodiment of my invention shown in Figs. 1 to 4 inclusive, and which constitutes a true division of my said co-pending application Ser. No. 645,919, now Patent No. 2,011,267, as well as a continuation in part of 35 my said co-pending application Ser. No. 613,244, filed May 24, 1932, the fabric is the same as disclosed in my said original application Ser. No. 541,245, now Patent No. 1,989,913 (that is to say, a main or weft thread is knitted back and forth upon all the needles of a full fashioned machine and a separate warp thread is introduced into each needle wale of the fabric and is confined to its own needle wale). There are as many warp 40 threads thus introduced as there are needle wales in the fabric at its widest extent.

The knitted fabric may be and preferably is a plain fabric such as made upon a full fashioned hosiery machine having a large number of sections upon each of which a stocking leg, or, if desired, a stocking leg and foot, is knitted. Any suitable hosiery yarn or thread may be employed as the main thread or weft thread, as, for example, silk, artificial silk, rayon, cotton or wool. 45

The yarns or threads may be changed from time to time in knitting the stocking as may be necessary, for example, at the end of the welt, and reinforcing threads may be introduced at desired points, as for example, in the heel and in the sole and at the toe.

The fabric is of the same character and structure as is represented in Fig. 3 of my said co-pending application Ser. No. 541,245, now Patent No. 1,989,913 and is run-proof or strongly run-resistant. The fabric is run-proof or strongly run-resistant in both directions throughout the entire extent thereof, and this effect is accomplished by introducing into each needle wale a separate thread or yarn as shown in Fig. 3 of my said application Ser. No. 541,245, now Patent No. 1,989,913 and also as shown in Figs. 3 and 9 of this application.

Each of the said threads or yarns which may be termed additional or secondary or warp threads, and which for convenience I will hereinafter refer to as warp threads, may be of any suitable material, but preferably silk. They may be introduced by means of a guide bar shown in my said parent application Ser. No. 645,919, now Patent No. 2,011,267 having thread guides, one for each needle, which latter are of the spring beard type. The main or weft thread may be introduced by a main thread carrier which is traversed to and fro in the manner and by the means existing in the well known Reading machine, as, for example, in the parts catalog of the Reading Full Fashioned Knitting Machine of Reading, Pa., copyrighted 1929, except that when the end of the leg or calf narrowings is reached, as shown in Figs. 1 and 2, the traverse of the main or weft thread carrier is in this embodiment of my invention, abruptly shortened at each end of its stroke, as indicated also in Fig. 4.

The main thread or yarn is indicated at 1 in Fig. 3, being traversed from edge to edge of each section of the fabric made at one time upon the machine, and the loops or stitches of the main yarn or thread are formed in the usual manner. In this first embodiment of the invention herein generically claimed, (namely, that shown in Figs. 1 to 4 inclusive), instead of successively shortening at intervals the traverses of the main thread carrier for the purpose of fashioning or narrowing the fabric, I employ narrowing points to transfer inward at the narrowings stitches each composed of a loop of the main knitting thread and a loop of the warp thread of that needle wale. In that embodiment of the same generic invention shown in Figs. 5 to 9, however, and as hereinafter referred to, the traverse of the main thread carrier is shortened at each end at each of the narrowings and this fact in conjunction with the use of narrowing points at each edge for transferring inward stitches composed of loops both of the main knitting thread and of a warp thread, effect the actual fashioning or narrowing of the fabric.

Referring to the character of the fabric knitted in accordance with both embodiments of the generic invention herein claimed, the warp threads are indicated at 2 in Figs. 3 and 9. Each warp thread lies in parallelism with the loop of the main knitting thread 1 inside the same, and at the top of the loop the warp thread 2 passes to the back of the previous loop and the thread 2 therein and then passes in front of the same down through the next loop when the same has been completed, passing through the back of such

loop and then participates in the formation of the next loop in the next course and the described operation is continued from course to course. Thus, in the fabric herein shown, the warp threads are collectively symmetrically 5 knitted into and incorporated with substantially all the stitches of all said needle wales, including fashioning wales. The said warp threads 2 do not enter into or become incorporated in the sinker wales.

It is unnecessary to describe in detail the means for incorporating the warp threads 2 with the main knitting thread 1, and it is sufficient to state that the guide bar for the warp threads has imparted thereto a movement lengthwise the machine and also a movement transverse to the line of needles of the machine, so that each warp thread guide enters between two next adjacent needles, preferably from rear to front, is then moved lengthwise the machine a distance of one 20 needle, is then swung rearwardly so as to cause each warp thread guide to pass through the needle line between the next two adjacent needles, and is then moved longitudinally in the opposite direction, thereby completing a square or rec- 25 tangle.

The warp threads are desirably supported upon a small warp beam and the number of the said warp threads 2 is the same as the number of active needles in any section or blank (that is, 30 the same as the greatest number of needles active at any time in the production of the hosiery fabric). Therefore the number of warp thread guides is the same as the total number of warp threads 2. My invention is, however, not limited 35 to the employment of a warp thread to each needle wale.

The stocking blank is begun at the commencement of the welt (if a welt be made), and after the knitting of the welt indicated at 3 in the several figures, the knitting of the leg portion 4 below the welt is continued of the full width of the welt down to the commencement of the narrowings, whether they be those just below the welt or whether they be those in the calf 45 or ankle portion of the leg. In knitting the blank in accordance with the disclosure in Figs. 1 to 4 inclusive, the traverse of the main thread carrier is continued of the full width to a point just below the calf narrowings, as indicated at 5—5 in Figs. 1 and 2, and at 5 in Fig. 4, at which point the traverse of the said main thread carrier is abruptly shortened as is indicated at 6—6 in Figs. 1 and 2 and at 6 in Fig. 4, after which the knitting is continued along parallel lines 7—7 of Fig. 1, during the knitting of which narrower portion 8 the reinforced portions 9—9 are knitted to constitute the heel tabs and which are to be turned into the position shown in Fig. 2 in order to have the strips or parts knitted thereonto that constitute the bottom of the foot.

When the point is reached where the narrowings should occur, I cause narrowing points of the machine at each side or edge of the blank to enter the desired or selected stitches or loops composed of the main or weft thread 1 and warp threads 2, and transfer the same laterally, so as to provide two inclined lines of narrowings indicated at 10—10 in Figs. 1 and 2, and at 10 in Figs. 3 and 4. This I do automatically by any suitable means, as, for example, the means shown in my said parent application Ser. No. 645,919 now Patent No. 2,011,267. In this manner, I produce the fabric structure represented in Figs. 3 and 4.

Referring more particularly to Figs. 3 and 4, the knitting is continued from the top or welt of the stocking down to a point just below the inclined lines of narrowings 10 of Figs. 1, 2, 3, and 4, and 5 the inclined lines of openings 11 of the calf or ankle portion, and then by automatically or otherwise shortening the traverse of the main thread carrier at each end of a traversing movement, the knitting is continued for the narrower fabric portion 8 of Fig. 1, as already described, which 10 narrower fabric is of sufficient width to provide for the instep as well as the heel tabs and the part of the fabric directly in longitudinal line with the said heel tabs. The toe is knitted as indicated 15 in my original application Ser. No. 541,245 now Patent No. 1,989,913. Thus, the knitting is terminated just below the termination of the lines of narrowing 10-10 at a horizontal line connecting the points 5-5, as to those needles where narrowings 20 have occurred by reason of the use of transfer points to make the said narrowings 10-10.

Notwithstanding the fact that the fabric is knitted of the full width from the upper end of the stocking down to a horizontal line connecting the points 5-5 of Figs. 1 and 2 (in this first embodiment, of my present generic invention), the stitches at the points where the fashioning or narrowing is to be provided are transferred inward 30 as indicated in Figs. 3 and 4 at 10 by means of narrowing points which may be of the usual number at each side or edge of the blank. Each stitch is transferred in to the extent of one or two needles, desirably not more than two, but the 35 traverse of the main thread carrier in this first embodiment of the present generic invention is continued for the full width of the fabric down to but not beyond a horizontal line connecting the points 5-5 of Figs. 1 and 2, but my present 40 generic invention is not limited thereto nor does it involve the same, which is shown only as an embodiment of a structure wherein is contained my said generic invention. Inasmuch as the warp threads 2 introduced by the endmost warp 45 guides and those near thereto remain in action, it will be evident that the warp threads 2 continue to be supplied to the same identical needles as before, although certain stitches (composed both of loops of the main thread and of the corresponding warp threads) are laterally shifted inward as indicated at 10 in Fig. 3. The result is to provide an inclined line of small openings 11, Figs. 1 to 4 inclusive, along each side of the fabric from 50 say a point indicated at 12-12 in Figs. 1 and 2 down to a transverse line indicated at 5'.

In Fig. 3 is represented the structure of the resulting fabric of this first embodiment of my said generic invention, and it will be observed that each of the openings 11 is traversed by one warp 60 thread 2, such thread becoming at once incorporated in the further knitting of the fabric in the two triangular portions 13-13 of Figs. 1 and 2, and the portion 13 of Figs. 3 and 4.

After the knitting of the entire blank has been 65 completed I trim off each edge of the blank along the lines of holes 11-11. This leaves entirely acceptable edges because of the non-run character of the fabric and the two inclined edges are then seamed together in any suitable manner to 70 make the stocking shown in Fig. 8. I may narrow or fashion by transferring of stiches to the extent of one needle or of two needles. So far as I am aware, it is new in the art to transfer both warp threads and the main knitting thread, 75 and it is to that feature that my said generic in-

vention is herein directed, irrespective of the number of warp threads, certain of which, however, are in fashioning wales, and loops thereof are laterally transferred with corresponding loops of the main knitting thread.

The narrowing points may be similar to and 5 may be mounted in a manner substantially the same as in the said Reading machine so that the proper dipping movements may be imparted thereto, and for explanation of the means for imparting such dipping movement, reference is made 10 to the said Reading machine and to the said catalog.

It will be understood that the progress of the main thread carrier across the bank of needles 15 starts substantially simultaneously with the commencement of the thread laying operation of the warp threads 2.

The instep and top of the foot portion of the fabric is indicated at 8 in Fig. 1. My invention 20 is of peculiar advantage with such type of foot as there shown (namely, the English type of foot) because the warp threads 2 of that portion of the blank continue without interruption from the top of the stocking down the leg and instep to the toe. The heel tabs are represented at 9-9 in Figs. 1 and 2, and after the blank of Fig. 1 has been knitted, the said blank is preferably cut along lines 14-14 from the bottom of the blank at 25 15-15 so as to produce the cut edges 16-16 of 30 Fig. 2 and to permit the heel tabs 9 to be turned up into the position shown in Fig. 2. The stocking blank having been transferred to a footer, the sole portions 17-17 are knitted as continuations 35 of the edges 18-18 of the heel tabs 9, and the toe 19 is knitted with the desired fashionings 20-20. The said heel tabs 9 may be fashioned as indicated at 21-21 of Fig. 1. The said heel tabs 9 are reinforced by the introduction into each of an additional weft thread by weft thread carriers 40 provided for that purpose as in the usual Reading machine.

It will be understood that the foot of the stocking shown in Figs. 2 and 8 is preferably formed in the following manner, especially in making the 45 stocking of the said first embodiment: When the warp thread fingers that introduce the warp threads at the parts where the narrowings are to occur are all out of action, the knitting of the fabric continues, but of the width indicated by 50 the line 22 in Fig. 1, down through the formation of the heel tabs 9-9 and desirably also of that same width as indicated at 7-7 in Fig. 1 down to the toe. If, however, I proceed by throwing out other warp thread fingers upon the termination 55 of the heel tabs 9-9 to reduce the width of the fabric to the width of the instep or top of the foot, the fabric thereafter knitted is of the reduced width indicated in Fig. 2 by the lines 60 16-16 down to the top of the toe, or I may proceed by continuing the knitting of the width indicated by the line 22 of Fig. 1 down to the toe and then cut the fabric lengthwise beginning 65 at the points 15, 15 of Fig. 1 and extending up sufficiently along the sides of the heel tabs 9, 9 to permit said heel tabs to be turned outwardly 70 as indicated in Fig. 2 for the subsequent knitting thereonto of the strips or portions 17, 17 which, when seamed together at their outer edges and to the sides of the instep portion 8 form the bottom of the foot.

It will be noted that the heel tabs 9 are provided with narrowings 21 of the same character as the narrowings 10 at the calf or ankle portion. 75

Referring now to the second embodiment of a full-fashioned or flat-knit stocking and blank, containing the broad generic invention herein claimed, the same is represented in Figs. 5 to 9 inclusive, the stocking shown in Fig. 8 being one made either from the blank of Figs. 1 to 4 or from the blank of Figs. 5, 6, 7 and 9.

In Figs. 5, 6, and 7 is shown in successive stages the blank that is made in accordance with the 0 said second embodiment. In said figures, the blank is preferably formed or provided with the same welt 3 as in the first embodiment, and it is to be understood that the structure of the fabric as to its non-run character by reason of the 5 presence of a separate warp thread in each needle wale is the same as in the first embodiment already described. The knitting of the blank is continued in the same manner and of the same width as the welt down to the point where the 10 first narrowing begins, whether the same be just below the welt or at the calf portion. For convenience of illustration and description, I have, in Figs. 5, 6 and 7, indicated the stocking blank as continued of the same width as the welt down 15 to a line 23—23. At that point I narrow at the customary or suitable intervals, as indicated diagrammatically along the edges of the blank shown in Figs. 5, 6 and 7. The said narrowings may be one or two needles in width at each edge of 20 the blank and in said figures I have indicated each narrowing as of one needle width. Instead of proceeding as in Figs. 1 to 4 inclusive, I preferably (when the line 23—23 is reached) automatically shorten at each end of its stroke the 25 traverse of the main thread carrier at intervals and I preferably do this in the automatic manner characteristic of the Reading machine as described in the said Parts Catalog. At the same time I cause the narrowing points to engage the 30 stitches each composed of a loop of the main knitting thread and a loop of the correlated warp threads and to shift the same inward preferably to the extent of one needle wale each, thus producing the effect which is shown upon an enlarged scale in Fig. 9 at a number of points 24 35 in Fig. 9. An examination of the said Fig. 9 will show that wherever the inward transfer of a stitch composed of a loop of the main knitting thread and a loop of a warp thread occurs, the 40 same is superimposed upon a stitch in the next needle wale, likewise composed of a loop of the main knitting thread and a loop of the warp thread of that needle wale. Inasmuch as the 45 traverse of the main knitting thread is at the same time automatically shortened wherever the transfer points shift the stitches inward as described, it will be evident that the warp thread ends of those wales to which the main knitting thread is no longer supplied, are caused or permitted to trail out as indicated more or less diagrammatically at 25 in Figs. 5, 6, 7, and 9, it 50 being evident that the said trailing ends are still in their respective warp guides. These trailing ends (the length whereof I have merely diagrammatically indicated and which may each be such as to extend to the toe of the blank) are subsequently trimmed off prior to the seaming together of the lateral edges of the blank. The 55 said narrowings, which in this second embodiment containing the generic invention herein claimed, continue down to some suitable point, as, for example, that indicated by the line 26—26 in Figs. 5, 6 and 7, and thereafter the knitting of the instep portion of the foot, the heel tabs, the 60 sole of the foot and the toe is or may be the 65

same as that described with respect to Figs. 1 to 4 inclusive, and the same reference characters are applied to both sets of figures. In either case, the completed stocking is that shown in Fig. 8, to which the same numerals are applied.

It will be understood that the full-fashioned or flat-knit stocking or stocking blank knitted in accordance with either embodiment of the generic invention that is herein claimed, is herein shown as composed substantially throughout, as to the main or body or weft thread, of accurately measured, non-robed, equal-length needle loops or stitches, and that each needle wale of the stocking blank from edge to edge thereof and including the fashioning wales are herein shown as having knitted successively into the stitches or loops thereof a separate warp thread, each needle loop or stitch of each warp thread being coordinately apportioned as to the length of threads constituting the same to the measured, corresponding needle loop or stitch of the said body thread, thereby preserving substantially normal lateral expansibility of the stocking, the fashioning stitches of the fashioning wales comprising laterally transferred stitches, each containing a loop of the said body thread and a loop of the warp thread pertaining to the respective wale of the fashioning wales. The stocking is substantially fully laterally expansible, as well as of a non-run or strongly run-resistant character. It will be observed that the warp threads extend uninterruptedly along the front of the leg into the instep of the foot in the respective needle wales. I provide in both embodiments a warp thread in substantially each needle wale, 35 but may, particularly in the first embodiment, omit them from certain lateral edge wales, and it is to be understood that my invention is not limited to a warp thread to each needle wale, since, as hereinbefore stated, my invention comprehends a shaped or fashioned knitted fabric having courses composed of a knitted body thread, and of a series of warp threads extending lengthwise the fabric and respectively knitted in loops in successive courses into different loops 40 of said body thread in such courses and including fashioning needle wales of the fabric, stitches at the shaped or fashioned areas of said fabric being each composed of a loop of said body thread and a loop of one of said warp threads, 45 together laterally transferred, thereby to shape or fashion the said fabric.

It will also be observed that the edges of the stocking blank are seamed or secured together along the sides and bottom of the foot and along the back of the leg. It will be observed that the laterally transferred loops, each containing a loop of the body or main thread and a loop of the warp thread pertaining to the respective wale of the fashioning wales, include loops at the calf or 55 ankle portions of the stocking and also at the heel portions. Thus the stocking is fashioned by laterally transferring stitches each comprising a loop of the body or main thread and a loop of a warp thread in each wale from which lateral 60 transfer is made.

Both illustrative embodiments of my invention present or disclose a fashioned knitted stocking blank comprising weft knitted courses of plain loops and warp knitted courses of loops, one warp 70 course for each wale of the fabric and each warp course having a loop for every loop in the wale in which the warp course is arranged, said fabric having a weft loop in certain courses and the associated warp loops transferred to the next 75

wales for narrowing the leg fabric. The term "warp course" is herein employed to indicate a warp thread as it lies in a needle wale of the fabric.

Having thus described two illustrative embodiments of a full-fashioned or flat-knit, non-run or strongly run-resistant stocking containing my generic invention herein claimed, and the best mode known to me for making the same, it is to be understood that although specific terms are employed, they are used in a generic and descriptive sense and that what is claimed in this case is the generic invention involving the transfer for narrowing purposes of stitches each comprising a loop of the main or body thread and a loop of a warp thread in each wale from which lateral transfer is made,—the more specific invention which includes also the knitting of the blank of full width at least to some extent past the commencement of the narrowings in the leg, and preferably down to the toe, being claimed in my co-pending application Ser. No. 700,193, filed November 29, 1933 now Patent No. 1,978,408.

I claim:

1. A substantially fully laterally expansible, non-run or strongly run-resistant full-fashioned or flat-knit stocking, comprising substantially throughout as to the body thread accurately measured, non-robbed, equal length needle loops or stitches, substantially each needle wale of the said stocking from edge to edge of the blank therefor and including the fashioning wales, having knitted successively into the stitches or loops thereof a separate warp thread, each needle loop or stitch of each warp thread being coordinately apportioned as to the length of thread constituting the same to the measured, corresponding needle loop or stitch of the said body thread, thereby preserving substantially normal lateral expansibility of the stocking, the fashioning stitches of the fashioning wales comprising laterally transferred stitches, each containing a loop of the said body thread and a loop of the warp thread pertaining to the respective wale of the fashioning wales.

2. A substantially fully laterally expansible, non-run or strongly run-resistant full-fashioned or flat-knit stocking, comprising substantially throughout as to the body thread accurately measured, non-robbed, equal length needle loops or stitches, substantially each needle wale of the said stocking from edge to edge of the blank therefor and including the fashioning wales, having knitted successively into the stitches or loops thereof a separate warp thread, each needle loop or stitch of each warp thread being coordinately apportioned as to the length of thread constituting the same to the measured, corresponding needle loop or stitch of the said body thread, thereby preserving substantially normal lateral expansibility of the stocking, the warp threads extending uninterruptedly from the front of the leg into the instep of the foot in the respective needle wales thereof, the fashioning stitches of the fashioning wales comprising laterally transferred stitches, each containing a loop of the said body thread and a loop of the warp thread pertaining to the respective wale of the fashioning wales.

3. A substantially fully laterally expansible, non-run or strongly run-resistant full-fashioned or flat-knit stocking, comprising substantially throughout as to the body thread accurately measured, non-robbed, equal length needle loops or stitches, substantially each needle wale of the

said stocking from edge to edge of the blank therefor and including the fashioning wales, having knitted successively into the stitches or loops thereof a separate warp thread, each needle loop or stitch of each warp thread being coordinately apportioned as to the length of thread constituting the same to the measured, corresponding needle loop or stitch of the said body thread, thereby preserving substantially normal lateral expansibility of the stocking, the fashioning stitches of the fashioning wales comprising laterally transferred stitches, each containing a loop of the body thread and a loop of the warp thread pertaining to the respective wale of the fashioning wales, the edges of the stocking blank being seamed or secured together along the sides and bottom of the foot and along the back of the leg.

4. A substantially fully laterally expansible, non-run or strongly run-resistant full-fashioned or flat-knit stocking, comprising substantially throughout as to the body thread accurately measured, non-robbed, equal length needle loops or stitches, substantially each needle wale of the said stocking from edge to edge of the blank therefor and including the fashioning wales, having knitted successively into the stitches or loops thereof a separate warp thread, each needle loop or stitch of each warp thread being coordinately apportioned as to the length of thread constituting the same to the measured, corresponding needle loop or stitch of the said body thread, thereby preserving substantially normal lateral expansibility of the stocking, the fashioning stitches of the fashioning wales comprising laterally transferred stitches, each containing a loop of the said body thread and a loop of the warp thread pertaining to the respective wale of the fashioning wales, said laterally transferred loops of fashioning wales including loops at the calf or ankle portions of the stocking.

5. A substantially fully laterally expansible, non-run or strongly run-resistant full-fashioned or flat-knit stocking, comprising substantially throughout as to the body thread accurately measured, non-robbed, equal length needle loops or stitches, substantially each needle wale of the said stocking from edge to edge of the blank therefor and including the fashioning wales, having knitted successively into the stitches or loops thereof a separate warp thread, each needle loop or stitch of each warp thread being coordinately apportioned as to the length of thread constituting the same to the measured, corresponding needle loop or stitch of the said body thread, thereby preserving substantially normal lateral expansibility of the stocking, the fashioning stitches of the fashioning wales comprising laterally transferred stitches, each containing a loop of the said body thread and a loop of the warp thread pertaining to the respective wale of the fashioning wales, said laterally transferred loops of fashioning wales including loops at the calf or ankle portion of the stocking and also at the heel portions.

6. That method of knitting a run-proof or strongly run-resistant flat-knit stocking which includes knitting the blank for at least the leg of the stocking by forming loops course by course from a body thread and a separate warp thread for substantially each needle wale from edge to edge of said blank; fashioning the stocking by laterally transferring stitches each comprising a loop of the body thread and a loop of the warp thread in each wale from which lateral transfer is made; completing the foot portion including

heel and toe, and thereafter seaming or securing together the edges of the fabric blank.

7. That method of knitting a substantially fully laterally expansible, run-proof or strongly run-resistant flat-knit stocking which includes knitting the blank for at least the leg of the stocking by forming loops course by course from a body thread and a separate warp thread for substantially each needle wale from edge to edge of said blank; fashioning the stocking by laterally transferring at the edge portions of the calf or ankle portion of the fabric blank stitches each comprising a loop of the body thread and a loop of the warp thread in each wale from which lateral transfer is made; completing the foot portion including heel and toe, and thereafter seaming or securing together the edges of the fabric blank.

8. That method of knitting a substantially fully laterally expansible, run-proof or strongly run-resistant flat-knit stocking which includes knitting the blank for at least the leg of the stocking by forming loops course by course from a body thread and a separate warp thread for substantially each needle wale from edge to edge of said blank; fashioning the stocking by laterally transferring stitches each comprising a loop of the body thread and a loop of the warp thread in each wale from which lateral transfer is made; continuing the knitting of the warp threads of the front part of the leg uninterruptedly into the corresponding needle wales of the instep of the foot; completing the foot portion including heel and toe, and thereafter seaming or securing together the edges of the fabric blank.

9. A non-run or strongly run-resistant flat-knit stocking, substantially each needle wale of the said stocking from edge to edge of the blank therefor, and including the fashioning wales, having knitted successively into the stitches or loops thereof a separate warp thread, the fashioning stitches of the fashioning wales comprising laterally transferred stitches, each containing a loop of the said body thread and a loop of the warp thread pertaining to the respective wale of the fashioning wales.

10. A stocking according to claim 9, having the edges of the stocking blank seamed or secured together along the sides and bottom of the foot and along the back of the leg.

11. A fashioned knitted stocking blank comprising weft knitted courses of plain loops and warp knitted courses of loops, one warp course for each wale of the fabric and each warp course having a loop for every loop in the wale in which the warp course is arranged, said fabric having a weft loop in certain courses and the associated warp loops transferred to the next wales for narrowing the leg fabric.

12. That method of knitting a run-proof or strongly run-resistant full-fashioned stocking which includes knitting the blank for at least the leg of the stocking by forming loops course by course from a body thread and a separate warp thread for substantially each needle wale from edge to edge of said blank, fashioning the stocking by laterally transferring stitches each comprising a loop of the body thread and a loop of the warp thread in each wale from which lateral transfer is made; completing the foot portion including heel and toe, and thereafter seaming or securing together the edges of the fabric blank.

13. That method of knitting a run-proof or strongly run-resistant full-fashioned or flat-knit

stocking blank which includes knitting said blank for at least the leg of the stocking by forming loops course by course from a body thread and a series of warp threads, one for substantially each needle wale of said blank, said warp threads being thereby collectively knitted into substantially all the stitches of said needle wales, thereby to render the resulting fabric of a non-run character substantially throughout, and laterally transferring inward stitches of the said blank, each such stitch composed of a loop of said body thread and a loop of a warp thread, thereby to provide fashionings or narrowings.

14. That method of knitting a shaped or fashioned run-proof or strongly run-resistant fabric which includes knitting said fabric by forming loops course by course from a body thread and a series of warp threads, one for substantially each needle wale of said fabric, said warp threads being thereby collectively knitted into substantially all the stitches of said needle wales, thereby to render the resulting fabric of a non-run character substantially throughout, and laterally transferring stitches of said fabric, each such stitch composed of a loop of said body thread and a loop of a warp thread, thereby to shape the fabric.

15. A shaped or fashioned run-proof or strongly run-resistant fabric having courses of loops composed of a body thread and of a series of warp threads, one for substantially each needle wale of said fabric, said warp threads being collectively knitted into substantially all the stitches of said needle wales, thereby to render the resulting fabric of a non-run character substantially throughout, said fabric having stitches each composed of a loop of said body thread and a loop of a warp thread laterally transferred to shape the fabric.

16. A knitted blank for a run-proof or strongly run-resistant full-fashioned or flat-knit stocking, the courses whereby are composed of a knitted body thread and a series of warp threads one for substantially each needle wale of said fabric blank, said warp threads being collectively knitted into substantially all the stitches of said needle wales, thereby to render the said fabric blank of a non-run character substantially throughout, said fabric blank having stitches each composed of a loop of said body thread and a loop of a warp thread laterally transferred inward to narrow the fabric.

17. A shaped or fashioned knitted fabric having courses composed of a knitted body thread, and of a series of warp threads extending lengthwise the fabric and respectively knitted in loops in successive courses into different loops of said body thread in such courses, and including fashioning needle wales of the fabric, stitches at the shaped or fashioned areas of said fabric being each composed of a loop of said body thread and a loop of one of said warp threads, together laterally transferred, thereby to shape or fashion the said fabric.

18. A knitted blank for a run-proof or strongly run-resistant full-fashioned or flat knit stocking, the courses whereof are composed of loops or stitches of a knitted body thread and a series of knitted warp threads one for substantially each needle wale of said fabric blank, said warp threads being collectively knitted into substantially all the stitches of said needle wales from edge to edge thereof and including the so-called fashioning wales, thereby to render said fabric

blank of a non-run character substantially throughout, said fabric having at the narrowing areas stitches, each composed of a warp thread loop and a weft thread loop, laterally transferred from such fashioning needle wales.

19. That method of knitting a run-proof or strongly run-resistant full-fashioned or flat-knit stocking blank, which includes knitting said blank for at least the leg of the stocking by forming knitted loops or stitches course by course from a body thread and from a series of warp threads, one for substantially each needle wale of said fabric blank, said warp threads being thereby collectively knitted into substantially all the stitches of said needle wales from edge to edge thereof and including the so-called fashioning wales, thereby to render said fabric blank of a non-run character substantially throughout, and laterally transferring inward stitches, each composed of a warp thread loop and a weft thread loop, from such fashioning needle wales at the narrowing areas, thereby to provide fashionings or narrowings.

20. A full-fashioned or flat-knit run-proof or strongly run-resistant stocking or blank therefor, comprising a main or body yarn incorporated into all the wales from edge to edge and all the courses of at least the leg thereof, and a series of warp threads or yarns, one for substantially each needle wale from edge to edge of the said fabric and collectively knitted into substantially all the stitches of all said needle wales, so that substantially each stitch of the main yarn of the said fabric has a stitch of warp thread, to render the resulting fabric of a non-run character throughout, said stocking or blank therefore having, at opposite edge portions thereof at narrowing (fashioning) areas spaced lengthwise the stocking or blank, needle stitches, each composed of a warp thread loop and a weft thread loop, laterally transferred inward from needle wales that had each so received a warp thread.

21. A full-fashioned or flat-knit run-proof or strongly run-resistant stocking or blank therefor, comprising a main or body yarn incorporated into all the wales from edge to edge and all the courses of at least the leg thereof, and a series of warp threads or yarns, one for substantially each needle wale from edge to edge of the said fabric and collectively knitted into substantially all the stitches of all said needle wales, so that substantially each stitch of the main yarn of the said fabric has a stitch of a warp thread, to render the resulting fabric of a non-run character throughout, said stocking or blank having at opposite narrowing (fashioning) areas spaced lengthwise the stocking blank, a knitted stitch, composed of a warp thread loop and a weft thread loop, at each such area laterally transferred inward from a needle wale which wale had received a warp thread in each needle stitch thereof.

22. A full-fashioned or flat-knit run-proof or strongly run-resistant stocking or blank therefor, comprising a main or body yarn incorporated into all the wales from edge to edge and all the courses of at least the leg thereof, and a series of additional warp threads, or yarns, one for substantially each needle wale from edge to edge of the said fabric and collectively knitted into substantially all the stitches of all said needle wales, so that substantially each stitch of the main yarn of the said fabric has a stitch of an additional or warp thread, to render the resulting fabric of a non-run character throughout, said stocking

or blank having, at opposite narrowing (fashioning) areas spaced lengthwise the stocking or blank, both the warp and the weft thread constituents of a knitted stitch at each such area laterally transferred inward from a needle wale which wale had received a warp thread knitted in each weft thread loop thereof.

23. That method of knitting full-fashioned or flat-knit hosiery which is run-proof or strongly run-resistant throughout the entire extent thereof, comprising the following steps: introducing a main knitting thread and forming therewith course after course of regular loops throughout the extent of at least the leg portion of the hosiery blank; and introducing a separate warp thread into each loop of each needle wale of the fabric coincidently with the laying of the respective courses of the fabric and knitting the same into and with the main knitting thread loops of the said needle wales throughout the lengthwise and transverse extent of the said hosiery blank; and shaping the fabric at the selvage portions by causing narrowing points to shift stitches, each composed of a warp thread loop and a weft thread loop, laterally inward at intervals spaced lengthwise the blank corresponding substantially to the usual spacing of narrowings in full-fashioned hosiery.

24. A full-fashioned or flat-knit run-proof or strongly run-resistant stocking or selvaged blank therefor, comprising a main or body yarn or thread incorporated into all the needle wales from edge to edge thereof and including fashioning wales, and all the courses of at least the leg thereof, and a series of warp yarns or threads, one for substantially each needle wale from edge to edge of the said fabric and including the fashioning wales, and collectively symmetrically knitted into and with substantially all the stitches of all said needle wales, so that the respective knitted loops of each such warp thread lie in parallelism with the loops of the main thread with which each such warp thread loop is drawn into a loop in the knitting operation, so that substantially each stitch of said main or body yarn or thread of the said fabric has symmetrically incorporated therewith a stitch of a warp yarn or thread, to render the resulting fabric of a non-run character throughout from selvage to selvage, the leg blank being narrowed or fashioned by reason of stitches of needle wales transferred laterally inward at fashioning areas or points, each said transferred stitch being composed both of a warp thread loop and a weft thread loop, said stocking having a suitable heel, foot and toe.

25. That method of knitting a full-fashioned or flat-knit run-proof or strongly run-resistant stocking including the following steps: knitting a main yarn or thread by traversing the same from edge to edge of the blank in successive courses including the edge needle wales of the fabric, to form a flat selvaged blank for the leg of a stocking; throughout the knitting of said leg blank and coincidently with the laying of the respective courses of the loops of the main yarn or thread introducing and knitting with the said course-by-course knitting of the main yarn a separate warp thread symmetrically into and with substantially each needle wale of the fabric from edge to edge of the fabric, including the fashioning wales, and in so doing introducing each said warp thread to its own needle wale throughout the extent of such wale; whereby the said blank is rendered run-proof or strongly run-resistant

throughout the extent thereof from edge to edge including said fashioning wales, and shaped but uncut selvage edges are provided; and narrowing or fashioning the fabric during the knitting of the leg blank by causing transfer of stitches, each composed both of a warp thread loop and a weft thread loop, laterally inward at the selvage portions, as by the action of narrowing points of the full-fashioned knitting machine whereon the 10 stocking is knitted; knitting the heel, foot and toe, and suitably seaming the blank.

26. A full fashioned or flat-knit run-proof or
strongly run-resistant stocking consisting of a
main or body yarn incorporated into all the needle
wales from edge to edge and all the courses
thereof, and a series of warp threads or yarns,
one for substantially each needle wale from edge
to edge of the fabric, and each knitted symmetrically
into and with all the stitches of its own
needle wale and continued therein throughout the
continuance of that wale as a separate wale, so
that the sinker wales are devoid of warp threads,
the leg blank being narrowed or fashioned by
reason of stitches of needle wales transferred
25 laterally inward at fashioning areas or points,
each such transferred stitch being composed of
a warp thread loop and a weft thread loop; said
stocking having a heel, foot and toe.

30 27. A shaped or fashioned, selvaged knitted fabric having courses composed of a knitted body thread, and of a series of warp threads extending lengthwise the fabric and respectively knitted in loops in successive courses into different loops of said body thread in such courses and including 35 fashioning needle wales of the fabric, stitches at the shaped or fashioned areas of said fabric being each composed of a loop of said body thread and a loop of one of said warp threads, together laterally transferred, thereby to shape or fashion 40 the said fabric, said laterally transferred stitches including stitches originating and existing at the actual selvage edges of the fabric.

28. A shaped or fashioned run-proof or strongly
run-resistant, selvaged fabric having courses of
loops composed of a body thread and of a series
of warp threads, one for substantially each need-
le wale of said fabric, said warp threads being
collectively knitted into substantially all the
stitches of said needle wales, thereby to render
the resulting fabric of a non-run character sub-
stantially throughout, said fabric having stitches
each composed of a loop of said body thread and
a loop of a warp thread laterally transferred
to shape the fabric, said laterally transferred
stitches including stitches originating and exist-
ing at the actual selvage edges of the fabric.

29. That method of knitting a shaped or fashioned run-proof or strongly run-resistant, selvaged fabric which includes knitting said fabric by forming loops course by course from a body thread and a series of warp threads, one for substantially each needle wale of said fabric, said warp threads being thereby collectively knitted into substantially all the stitches of said needle wales, thereby to render the resulting fabric of a non-run character substantially throughout, and laterally transferring stitches of said fabric, including stitches originating and existing at the actual selvages of the fabric, each such stitch composed of a loop of said body thread and a loop of a warp thread, thereby to shape the fabric.

75 30. A shaped or fashioned knitted fabric having courses composed of a knitted body thread and of a series of warp threads extending lengthwise the fabric and respectively knitted in loops in

successive courses into different loops of said body thread in such courses and including fashioning needle wales of the fabric, stitches at the shaped or fashioned areas of said fabric being each composed of a loop of said body thread and a loop of one of said warp threads, together laterally transferred, thereby to shape or fashion the said fabric, said shaped or fashioned fabric having selvage edges wherat the said body thread is persistently returned, in unsevered condition, upon itself in a succeeding course, certain at least of said laterally transferred stitches being at said selvage edges. 5 10

31. A shaped or fashioned run-proof or strongly run-resistant fabric having courses of loops 15 composed of a body thread and of a series of warp threads, one for substantially each needle wale of said fabric, said warp threads being collectively knitted into substantially all the stitches of said needle wales, thereby to render the resulting fabric of a non-run character substantially throughout, said fabric having stitches each composed of a loop of said body thread and a loop of a warp thread laterally transferred to shape the fabric, said shaped or fashioned fabric having selvage edges whereat the said body thread is persistently returned, in unsevered condition, upon itself in a succeeding course, certain at least of said laterally transferred stitches being at said selvage edges. 20 25 30

32. That method of knitting a shaped or fashioned run-proof or strongly run-resistant, selvaged fabric which includes knitting said fabric by forming loops course by course from a body thread persistently returned, in unsevered condition, in a succeeding course upon itself, and a series of warp threads, one for substantially each needle wale of said fabric, said warp threads being thereby collectively knitted into substantially all the stitches of said needle wales, thereby to render the resulting fabric of a non-run character substantially throughout, and laterally transferring stitches of said fabric, including stitches originating and existing at the actual selvage edges of the fabric, each such stitch composed of a loop of said body thread and a loop of a warp thread, thereby to shape the fabric.

33. A warp and weft, flat knitted fabric having a weft thread extending from edge to edge in successive courses and having warp threads in certain needle wales thereof, the end weft loops of certain courses and the associated warp loops of said end weft loops being laterally transferred to adjacent wales for shaping the fabric.

34. A fashioned, warp and weft, flat knitted, 55
stocking blank having a weft thread extending
in knitted loops from edge to edge in successive
courses and having warp threads in certain need-
le wales thereof, the end weft loops of certain
courses of the leg portion of said stocking blank 60
and the associated warp loops of said end weft
loops being transferred to adjacent wales for nar-
rowing the leg portion of the blank and provid-
ing reinforced selavage edges at such portions

35. A full-fashioned or flat-knit run-proof or 65
strongly run-resistant stocking or selvaged blank
therefor, comprising a main or body yarn or
thread incorporated into all the needle wales
from edge to edge thereof and including fash- 70
ioning wales, and all the courses of at least the
leg thereof, and a series of warp yarns or threads,
one for substantially each needle wale from edge
to edge of the fabric and including the fashion-
ing wales, and collectively symmetrically knitted
into and with substantially all the stitches of all 75

5 said needle wales, so that the respective knitted loops of each such warp thread lie in parallelism with the loops of the main thread with which each such warp thread loop is drawn into a loop in the knitting operation, so that substantially each 10 stitch of said main or body yarn or thread of the said fabric has symmetrically incorporated therewith a stitch of a warp yarn or thread, to render the resulting fabric of a non-run character throughout from selavage to selavage, the said

warp yarns or threads being of the same character as the main yarn or thread so as to give a uniform structure and appearance to the resulting hosiery, stitches of the fashioning wales of the stocking being laterally transferred inward to 5 shape or fashion the stocking, each such laterally transferred stitch being composed both of a warp thread loop and a weft thread loop.

ELLSWORTH E. CARLSON. 10
